(57) **CLAIM**

The ornamental design for an industrial robot hand, as shown and described.

DESCRIPTION

FIG. 1 is a rear and right side perspective view of an industrial robot hand, showing my new design;

FIG. 2 is a front and left side perspective view thereof;

FIG. 3 is a front view thereof;

FIG. 4 is a rear side view thereof;

FIG. 5 is a top plan view thereof;

FIG. 6 is a bottom view thereof;

FIG. 7 is a left side view thereof;

FIG. 8 is a right side view thereof;

FIG. 9 is a rear and right side perspective view showing the industrial robot hand in which claws thereof are closed;

FIG. 10 is an exemplary front view showing the industrial robot hand attached to one industrial robot arm; and,

FIG. 11 is an exemplary front view showing the industrial robot hand attached to the other industrial robot arm.

The broken lines in the drawings depict unclaimed environmental subject matter.
